BASE FOR A PEN DESK SET OR SIMILAR ARTICLE

Harold A. Dunn, Franklin County, Ohio
(3237 McKinley Ave., Columbus, Ohio 43204)

Filed Feb. 18, 1970, Ser. No. 21,500

Term of patent 7 years

Int. Cl. D19—02
U.S. Cl. D74—5

FIG. 1 is a perspective view of a base for a pen desk set or similar article showing my new design;

FIG. 2 is a top plan view thereof; and

FIG. 3 is a side elevational view looking toward the side of the base opposite that shown in FIG. 1.

I claim:

The ornamental design for a base for a pen desk set or similar article, substantially as shown and described.
